UNITED STATES PATENT OFFICE.

VIRGINIA HELENE BIXBY, OF OMAHA, NEBRASKA.

DOLL.

Application filed July 25, 1924. Serial No. 728,223.

This invention relates to improvements in toys.

The primary object of this invention is the provision of a toy, such as a doll, which 5 may simulate a child, other human character, or animated objects.

A further object of this invention is the provision of a doll preferably formed of sheet material, such as paper, composition 10 material, or the like, embodying features which render the same anatomically correct in so far as location and movement of parts is concerned.

A further object of this invention is the 15 provision of a doll or analogous figure, including supporting body and head portions which are gradually turned laterally with respect to each other, so that as used in connection with a doll simulating a child, the 20 feet portions may be turned sidewise, the body or torso gradually turned toward the front, and the head facing substantially to the front.

A further object of this invention is the 25 provision of a doll embodying a novel supporting arrangement or leg construction.

A further object of this invention is the provision of a doll or analogous toy including a body portion, and laterally extending 30 arms which are free to move with respect to the body portion and disposed in partially overlapping relation therewith.

A further object of this invention is the 35 provision of novel means to facilitate relative assemblage of the parts of the doll.

A further object of this invention is the provision of a toy cut-out preferably simulating a doll, embodying novel features to facilitate the cutting of the parts of the doll 40 so that they may be easily assembled to provide a figure, which as to parts is substantially anatomically correct.

Other objects and advantages of this invention will be apparent during the course 45 of the following detailed description.

In the accompanying drawings, forming a part of this specification, and wherein similar reference characters designate corresponding parts throughout the several views,

50 Figure 1 is a plan view of a sheet of material, having the parts of a figured cut-out depicted thereon in developed form.

Figure 2 is a front elevation of a figure constructed in accordance with this invention.

55 Figure 3 is a rear view of a figure con-

structed in accordance with this invention.

Figure 4 is a side elevation of the figure or doll illustrated in Figures 2 and 3.

Figure 5 is a side view opposite to the 60 side view illustrated in Figure 4.

Figure 6 is a fragmentary perspective view of a portion of the doll illustrated in Figure 2, showing a novel structural feature thereof, which will permit the provision 65 of arms upon the doll or other figure which may be moved in so far as the body portion of the figure is concerned, notwithstanding the fact that the arms or other portions are in overlapping relation with the body.

70 Figure 7 is a cross sectional view, taken substantially on the line 7—7 of Figure 3.

Figure 8 is a fragmentary cross sectional view, illustrating certain structural features 75 of this invention.

Figure 9 is a fragmentary inside view of a leg construction of the doll illustrated in Figure 2.

Figure 10 is a rear elevation of the upper 80 portion of the doll illustrated in Figure 1, showing the parts after folding and preparation to a finishing operation.

In the drawings, wherein for the purpose of illustration is shown but the preferred embodiment of this invention, the letter A 85 generally designates the improved doll, which may be die stamped, or the parts of which may be provided in the form of cut-out parts upon a sheet of material 10, such as paper.

90 Referring to this invention as provided in the form of a cut-out, the sheet of material 10 is preferably elongated and rectangular in formation, having main parts 11 and 12 depicted thereon representative of front and rear views respectively of the child or other object which the doll represents. Each of the main parts or sections 11 and 12 preferably include a body portion 13; supporting leg portion 14; and head portion 15.

95 The relative positioning of the parts 13, 14 and 15 of each section 10 and 11 is important, since they determine the posture which the child assumes in the completed figure.

A preferred arrangement is that of illustrating the leg portions 14 of the main parts 11 and 12 as facing sideways, so that the feet 17 at the ends of the leg portions 14 are so turned as to provide a maximum bearing 100 surface, in that the same are shown in side elevation. The torso or body portions 13 turn gradually to the front and rear up-

wardly of the legs 14, till the head portions 15 of the parts 11 and 12 are respectively turned substantially full front and full rear. While this arrangement is desirable, the relative positioning of parts may be somewhat different, as used in connection with other features of this invention, although a benefit resulting therefrom is that of providing a figured toy which will stand in a perfectly natural position, affording a maximum supporting surface, and yet permit of substantially full front and rear views of the figure upwardly of the body or torso.

As the front and rear views or main parts 11 and 12 respectively are adapted for folding or positioning in abutting conforming relation, a novel expedient has been provided in connection with the formation of the doll as a cut-out, which is illustrated in Figures 1 and 10 of the drawings. The parts 11 and 12 are positioned in longitudinal relation with the head portions 15 thereof in proximate spaced relation. A strip of material 20 is delineated upon the sheet 10, intermediate the head portions 15, by means of arcuate side lines 21, which are preferably dotted and designate cutting lines. This strip of material 20 is provided with a straight line 23 thereon, extending transversely and at right angles to the line in which the parts 11 and 12 lie, so that after said parts or sections 11 and 12 have been cut out upon their marginal lines, they may be relatively folded upon the straight line 23; the strip 20 not having at yet been disconnected from the head portions 15. It is obvious that the straight line 23 thus furnishes a guide whereby the main parts of the invention may be relatively positioned in abutting and conforming relation. The position of the strip 20, or rather its appearance, after folding of the head portions 15 upon each other, is illustrated in Figure 10. The function of the strip 20 having been performed, the same may be severed from the head portions 15 by cutting along the arcuate marginal lines 25 designating the top of the head of the doll figure. From this description, it is obvious that the strip of material 20 is to be discarded after the folds 11 and 12 have been placed in relative positions, and that said strip forms no part of the finished figure, but merely furnishes a guide for the placing of the front and rear parts of the doll, as it can be readily understood and is found in practice that a child or other person cannot accurately place the parts in conforming and abutting relation as accurately as is possible when done as herein described. There are of course no abrupt edges or outstanding parts of the head portions after severance of the strip 20, since both head portions 15 are cut upon a single upper arcuate line.

65 Referring to the supporting or leg con-

struction, it is to be noted that an auxiliary part is provided, contiguous with each section 11 and 12, outwardly of the feet portion 17 thereof which, in fact, are inner flaps or folds 30 for cooperation with the leg portions 14 of said main parts or sections 11 and 12. Each of these parts 30 preferably include a foot portion 31 in abutting relation at its bottom surface with the bottom surface of the foot 17; and the leg portion 30 extends outwardly from the foot 31. The parts 30 as before mentioned provide inner folds for each leg 14, which are adapted for folding upon the lines 36 or in the space intermediate the bottoms of feet 17 and 31; thus insuring that the legs of the completed figure are of stable construction and provide finished inner and outer flaps, as is illustrated in Figures 2 and 3 of the drawings, showing inner and outer sides of both legs.

The sections 11 and 12 when placed in abutting relation as hereinbefore described, are pasted, glued or otherwise secured together throughout the major abutting surfaces thereof, although it is preferred that at a point just upwardly of the lower marginal edge 35, defining the bottom of the body portions 13, said strips 11 and 12 are spread apart, as to accommodate the upper ends of the leg flaps 30 intermediate the lower portions of the body sides 13, substantially as is illustrated in Figure 8 of the drawings. Thus, the legs of the completed figure are in separated substantially V-shaped relation and freely movable with respect to each other, due to flexibility of material from which the doll is formed. In the completed figure, it is preferred that the legs of the doll be disposed in planes which are slightly overlapping, with one leg to one side of the other, so that the supporting surfaces provided by the bottom edges 36 of the doll feet are relatively extended to provide a maximum length of supporting surface, consistent with a natural posture which the child assumes.

Referring to the section 11 of the improved doll A, as illustrated in Figure 1, an outstanding arm portion 40 is provided on the body 13, and a relatively heavy or other contrasting line 41 is struck for a certain distance along a margin of the body 13 to denote a cutting line, which must be severed to permit of free arm movement in accordance with the novel feature of this invention, and as will subsequently appear. The body 13 of the section or rear view 12 is likewise provided with an outstanding arm 43, which when the sections or folds 11 and 12 are in abutting relation conforms in abutting relation with the outstanding arm 40 of the section 11, substantially as is illustrated in Figure 7 of the drawings. A cutting line 44 is also designated at a junc-

ture of the arm 43 with the body portion 13, so that the arm may be partly severed from the body 13. When the sections 11 and 12 are in folded relation, it will be noted that the arm portions 40 and 43, which form a single arm of the completed figure, are in abutting relation throughout their major areas and are pasted or glued together on said areas. As is illustrated in Figures 2 and 3 of the drawings, the arm fold or portion 43 is in overlapping relation with the body portions 13, and the areas of said overlapping portions of the arm and body are not pasted together, but as is illustrated in Figure 7, it is preferred that the completed arm outstand slightly from the body which it overlaps as to provide a natural appearance of the arm, and which feature of providing an arm which is only connected to the body at the socket thereof permits of the dressing of the doll in various types of garments which appear entirely natural.

Referring again to the part or section 11 of the doll, and as depicted in Figure 1 of the drawings, the other arm portion 48 thereof is preferably bent so that the hand and forearm portion thereof are formed as a part of the body 13. The marginal edges 49 of this arm portion 48 which are outlined upon the body 13, are in contrast in any approved manner with respect to the other marginal edges of the section 11 to denote cutting lines. A line 50^a adjacent the socket of the arm portion 48 is also contrastingly delineated, as a cutting line, so that the arm portion 48 may move freely in accordance with the feature hereinbefore described for the arm portions 40 and 43. Upon the rear fold or section 12, the arm portion 50 extends laterally of the body 13; the same appearing to extend forwardly of the child, so that the forearm and hand portion of the arm part 50 does not appear upon section 12. A cutting line 52 is contrasted, in any approved manner upon the section 12, to denote that portion of the arm 50 which must be severed from the body 13.

When the front and rear folds or sections 11 and 12 are in abutting relation, the abutting areas of the arm portions 48 and 50 are pasted or otherwise glued together. It is to be noted that a portion of the arm part 48 at its upper end or near the socket of said arm portion 48 overlaps the body portion 13 of the section 12, and these overlapping parts of the arm portion 48 and body 13 of the section 12 are not pasted together but remain unpasted so that the arm 48 and its rear portion 50 may be freely movable to outstand from the completed body of the doll, substantially as is illustrated in Figure 6 of the drawings. In this view, it is shown that the cutting of the forearm of the arm portion 48 from the section 11 leaves a

recess. Upon securing of the body portions of flaps 11 and 12 together, this recess is in effect a socket, but the forearm of the arm part 48 outstands from this socket 55, as to provide a natural appearance of the completed arm.

From the foregoing description of the arm construction of the improved doll, as completed, it is obvious that the arms may be located in various relations with respect to each other and with respect to the body of the figure; the overlapping portions of the arms and the body portion, except at the sockets of the arms, being unsecured so that the arms will appear natural and out-standing from the body portion, so that no matter what the posture of the child or positioning of the arm and body parts, garments may be placed upon the doll.

The term "doll" as used in this specification and in the claims is not to be limited to the figure of a child, but is to be broadly construed, and may include persons, animals, animated figures, and other objects in connection with which novel features of this invention may be employed. While the preferred embodiment is that of a cut-out as illustrated in Figure 1, it is contemplated to die cut the various parts of the invention, or form the same as complete.

Various changes in the shape, size or arrangement of parts may be made to the form of the invention, without departing from the spirit of this invention or the scope of the claims.

I claim:

1. A cut-out doll having a body portion, a head portion and only two pendant leg portions at least partially overlapping, said leg portions each terminating in a laterally directed foot portion and being formed respectively on separate body parts which are secured together face to face, at least one leg portion being free to be deflected in a plane inclined to the plane of the other leg portion and to the plane of the body portion, which plane it intersects at a point sufficiently adjacent the center of the gravity of the doll to form with the other leg portion a complete means to support the doll erect, each of the leg portions having two registering and facing parts, one of which is an extension of a body part, the other being positioned over a face of the first mentioned leg part.

2. A cut-out doll having a body portion, a head portion and only two pendant leg portions at least partially overlapping, and each terminating in a foot portion, the two foot portions being laterally extended in the same direction, said leg portions being formed respectively on separate body parts which are secured together face to face and at least one leg portion being free to be deflected in a plane inclined to the plane of the other leg

portion and to the plane of the body portion, which plane it intersects at a point sufficiently adjacent the center of the gravity of the doll to form with the other leg portion a complete means to support the doll erect, each of the leg portions and foot portions having two registering and facing parts, one of which is an extension of a body part, the other positioned over a face of the first mentioned leg and foot part.

3. A cut-out doll having a body portion, a head portion and only two pendant leg portions at least partially overlapping, and each terminating in a foot portion, the two foot portions being laterally extended in the same direction, said leg portions being formed respectively on separate body parts which are secured together and at least one leg portion being free to be deflected in a plane inclined to the plane of the other leg portion and to the plane of the body portion, which plane it intersects at a point sufficiently adjacent the center of the gravity of the doll to form with the other leg portion a complete means to support the doll erect, each of the leg portions having two facing registering parts, at least one of which is an extension of a body part, the other being folded over the inner face of the first mentioned leg part and having a concealed terminus.

4. A cut-out doll having a body portion and a head portion formed of two parts secured face to face, the doll having only two pendant leg portions, said legs being formed one on each body part and one being free to be deflected in a plane inclined to the plane of the other leg portion and to the plane of the body portion, which plane it intersects at a point sufficiently adjacent the center of the gravity of the doll to form with the other leg portion a complete means to support the doll erect, said leg portions each having an extension to form a facing part, the extension being folded over one face of the leg portion and registering therewith.

5. A cut-out doll having a body portion and a head portion formed of two parts secured face to face, the doll having only two pendant leg portions, said legs being formed one on each body part and at least one being free to be deflected in a plane inclined to the plane of the other leg portion and to the plane of the body portion, which plane it intersects at a point sufficiently adjacent the center of the gravity of the doll to form with the other leg portion a complete means to support the doll erect, said leg portions each having a longitudinal extension to form a facing part, the extension being folded at the terminus of the leg por-

tion upwardly over one face of the leg portion and registering therewith.

6. A blank for a cut-out doll having marking for "front" and "rear" doll parts, each part comprising a body portion, a single main leg portion and a single auxiliary leg portion, the body portions being adapted to be secured together face to face to make a complete doll body, and the main and auxiliary leg portions of each part being of substantially the same shape and arranged adjacent one another and having substantially the same contour, whereby the auxiliary leg portion may be folded over the adjacent main leg portion.

7. A blank for a cut out doll having marking for "front" and "rear" doll parts, each part comprising a body portion, a single main leg portion and a single auxiliary leg portion, the body portions being adapted to be secured together face to face to make a complete doll body, and the main and auxiliary leg portions of each part being of substantially the same shape and arranged adjacent one another in longitudinal alignment whereby the auxiliary leg portion may be folded over the adjacent main leg portion.

8. A blank for a cut-out doll having marking for "front" and "rear" doll parts, said parts being arranged adjacent one another in substantially longitudinal alignment whereby the blank may be folded to bring the parts face to face, each of said parts comprising a body portion, a single main leg portion and a single auxiliary leg portion, said leg portions having substantially the same contour and being arranged adjacent one another whereby the blank may be again folded between the main and auxiliary leg portions to bring the same face to face, the leg portions of each part making a complete doll leg independent of the leg portions on the other part.

9. A blank for a cut-out doll having marking for "front" and "rear" doll parts, said parts being arranged adjacent one another in substantially longitudinal alignment whereby the blank may be folded to bring the parts face to face, each of said parts comprising a body portion, a single main leg portion and a single auxiliary leg portion, said leg portions having substantially the same contour and being arranged adjacent one another in substantially longitudinal alignment whereby the blank may be again folded between the main and auxiliary leg portions to bring the same face to face, the leg portions of each part making a complete doll leg independent of the leg portions on the other part.

VIRGINIA HELENE BIXBY.
